UNITED STATES PATENT OFFICE.

DANIEL W. RANTINE, OF NEW YORK, N. Y.

ROTARY VALVE.

SPECIFICATION forming part of Letters Patent No. 746,574, dated December 8, 1903.

Application filed January 29, 1903. Serial No. 141,018. (No model.)

To all whom it may concern:

Be it known that I, DANIEL WILLIAM RANTINE, a citizen of the United States, and a resident of the city of New York, borough of Brooklyn, in the county of Kings and State New York, have invented a new and Improved Rotary Valve, of which the following is a full, clear, and exact description.

The invention relates to steam-engines; and its object is to provide a new and improved rotary valve which is simple and durable in construction, very effective in operation, and arranged to accurately control the admission and exhaust of the motive agent, and thereby insure an easy running of the engine and utilization of the motive agent to the fullest advantage.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement as applied. Fig. 2 is an enlarged sectional side elevation of the improvement. Fig. 3 is a similar view of the same, showing the valve in a different position. Fig. 4 is an enlarged plan view of the valve, and Fig. 5 is a sectional plan view of the same on the line 5-5 of Fig. 2.

The engine on which the improved rotary valve is applied is provided with the usual cylinder A, in which reciprocates a piston B, connected by suitable means with the main shaft C of the engine, as plainly indicated in Fig. 1. From the ends of the cylinder A lead cylinder-ports *a* and *b* to register with ports *c* and *d*, respectively, formed in a cylindrical valve-casing E, secured to one side of the cylinder A, as plainly illustrated in the drawings. The valve-casing E is provided at or near its middle with an inlet-pipe F, connected with a boiler or other suitable source of motive-agent supply, and from the ends of the said valve-casing E lead exhaust-pipes G and G' for carrying off the exhaust motive agent.

Within the cylindrical casing E are arranged valve-heads H and H', spaced apart

and located on opposite sides of the inlet-pipe F, and the said valve-heads H and H' are secured on a valve-stem I, extending through a stuffing-box J and carrying at its lower end a bevel gear-wheel K in mesh with a bevel-pinion K' on the shaft C, so that when the engine is in motion and the shaft C is rotated then the pinion K' imparts a rotary motion to the bevel gear-wheel K to rotate the stem I and the heads H and H', secured thereon. The gearing described is so proportioned that the shaft C makes two revolutions to one revolution of the valve-heads H and H'. 65

The valve-head H is provided with two inlet-ports *e* and *e'*, (see Figs. 2 and 5,) leading from the inner faces of the valve-head to the periphery thereof at diametrically opposite points, and exhaust-ports *f* and *f'* lead from the periphery of the head H to the outer face of the said head, and the said ports *e*, *e'*, *f*, and *f'* are adapted to register alternately with the port *c*, leading to the cylinder-port *a*. 70

The valve-head H' is provided with inlet-ports *e²* and *e³*, similar to the ports *e* and *e'*, and the said valve-head H' is also provided with exhaust-ports *f²* and *f³*, similar to the exhaust-ports *f* and *f'*, above mentioned. The ports *e²*, *e³*, *f²*, and *f³* are adapted to register alternately with the port *d*, leading to the cylinder-port *b*; but the inlet-ports *e* and *e'* of the valve-head H register with the port *c* at the time the exhaust-ports *f²* and *f³* of the valve-head H' register with the port *d*, (see Fig. 2,) 85 and when the exhaust-ports *f* and *f'* of the valve-head H register with the port *c* then the inlet-ports *e²* and *e³* of the valve-head H' register with the port *d*, as plainly indicated in Fig. 3. Now when the several parts are 90 in the position shown in Fig. 2 then the steam passing into the valve-casing E by way of the inlet-pipe F passes through the ports *e*, *c*, and *a* into the upper end of the cylinder A to act on the piston B therein to push the latter downward in the direction of the arrow *a'*. The steam in front of this piston B now passes down the cylinder A by way of the ports *b*, *d*, and *f²* to the lower end of the valve-casing E and through the exhaust-pipe G' to the outer 100 air. As the valve-heads H and H' are rotating in unison it is evident that when the piston B nears the end of its downward stroke then the ports *e* and *f²* move out of engage-

ment with the ports *c* and *d*, and the ports *f* and *e*² now move in register with the said ports *c* and *d*, respectively, whereby the live steam is now directed through the ports *e*², 5 *d*, and *b* into the lower end of the cylinder to force the piston *B* upward in the inverse direction of the arrow *a'*, and the exhaust-steam in front of this piston now passes out of the upper end of the cylinder by way of the ports 10 *a*, *c*, and *f*, the upper end of the casing *E*, and the exhaust-pipe *G*. When the piston *B* nears the end of its upward stroke, then the further rotation of the valve-heads *H* and *H'* has brought the port *e'* in register with the 15 port *c* and the port *f'* in register with the port *d*, so that live steam now passes again into the upper end of the cylinder by way of the head *H*, while the exhaust from the lower portion of the cylinder passes out by way of 20 the head *H'* to the exhaust-pipe *G'*.

Having thus described my invention, I claim as new and desire to secure by Letters Patent—

1. A rotary valve having a cylindrical valve-head, provided with a pair of inlet-ports and 25 and a pair of outlet-ports, the pairs of ports being disposed at angles one to the other, and the ports in one pair extending from diametrical points on the periphery of the head 30 through one face thereof, and the other pair of ports extending from the periphery of the head through the other face thereof, as set forth.

2. A rotary valve comprising a revolving 35 valve-stem, and spaced cylindrical valve-heads secured on the said stem, the valve-heads having inlet-ports leading from the inner faces of the heads to the periphery thereof, at diametrically opposite points, and 40 the said valve-heads having exhaust-ports leading from diametrical points on the periphery of the heads to the outer faces thereof, as set forth.

3. A rotary valve comprising a cylindrical 45 valve-casing having an inlet at the middle and exhausts at the ends, a rotary valve-stem in the said casing, and cylindrical valve-heads secured on the said stem and spaced from each other at opposite sides of the inlet, each valve- 50 head having inlet-ports leading from the inner face of the head to the periphery thereof, at diametrically opposite points, and outlet-ports leading from diametrically opposite points on the periphery of the head, to 55 the outer face thereof, as set forth.

4. A rotary valve comprising a cylindrical 60 valve-casing having an inlet at the middle and exhausts at the ends, a rotary valve-stem in the said casing, and cylindrical valve-heads secured on the said stem and spaced from each other at opposite sides of the inlet, each valve- 65 head having inlet-ports leading from the inner face of the head to the periphery thereof, at diametrically opposite points, and outlet-ports leading from diametrically oppo-

site points on the periphery of the head, to the outer face thereof, the said inlet and exhaust ports having their peripheral ends disposed alternately and in the same plane, as set forth. 70

5. A rotary valve having a valve-casing provided with an inlet at the middle and exhausts at the ends, and spaced valve-heads in the said casing, rotating in unison, the heads having inlet-ports and exhaust-ports, 75 of which the inlet-ports lead from the inner faces of the heads to the periphery thereof, and the exhaust-ports lead from the periphery of the heads to the outer faces thereof, the peripheral ends of the inlet-ports of one head 80 being arranged in the same axial plane as that containing the exhaust-ports of the other head, as set forth.

6. A rotary valve, comprising a cylinder having cylinder-ports, a valve-casing on the 85 said cylinder, having ports in register with the said cylinder-ports, the valve-casing having an inlet at or near the middle and exhausts at the ends, spaced cylinder-heads mounted to rotate in the said casing, spaced from each 90 other on opposite sides of the said inlet, each valve-head having inlet-ports leading from the inner face of the head to the periphery thereof, at diametrically opposite points, the outlet-ports leading from diametrically opposite 95 points of the periphery of the head, to the outer face thereof, the peripheral ends of the inlet-ports of one head being arranged in the same axial plane as that containing the exhaust-ports of the other head, a valve-stem 100 carrying the said heads, a bevel gear-wheel on the said stem, and a bevel-pinion secured on the main shaft of the engine, in mesh with the said bevel gear-wheel, to rotate the said valve-heads once for every two revolutions of 105 the main shaft, as set forth.

7. In the construction of a cylindrical rotary valve, a valve-head having both ends hollow and having four longitudinal ports on the cylindrical side, two opposite ports of the 110 four being open to one hollow end and the two other ports being open to the other hollow end, as set forth.

8. The combination with a cylindrical valve-casing having a steam-inlet intermediately of 115 its ends and an exhaust at each end, of two cylindrical rotary valve-heads in the casing, each valve-head having both ends hollow and provided with two pairs of ports, one pair being open to one end of the head and the other 120 pair to the opposite end of said head, as set forth.

In testimony whereof I have signed my name to this specification in the presence of two subscribing witnesses.

DANIEL W. RANTINE.
